COLLAR CLIP OR SIMILAR ARTICLE

Donald V. Carnevale, New York, N. Y.

Application November 2, 1949, Serial No. 5,832

Term of patent 7 years

(Cl. D17—8)

To all whom it may concern:

Be it known that I, Donald V. Carnevale, a citizen of the United States of America, residing in New York city, county of New York, and State of New York, have invented a new, original, and ornamental Design for a Collar Clip or Similar Article, of which the following is a specification, reference being had to the accompanying drawing, forming part thereof, wherein,

Figure 1 is a front elevational view of a collar clip, showing my new design in closed position.

Figure 2 is a rear elevational view of the collar clip.

Figure 3 is a side elevational view of the collar clip, and

Figure 4 is a view similar to Figure 3, showing the collar clip in open position.

The essential feature of my design resides in the specific configuration of the clasp element.

I claim:

The ornamental design for a collar clip or similar article, substantially as shown and described.

DONALD V. CARNEVALE.
